[57] ABSTRACT

Tools for the installation and removal of bits in mining and digging machinery, wherein the bits are characterized by the fact that that portion of the bit body which extends outwardly of the bit mounting means and is engageable by a tool during the extraction process has a smooth, uninterrupted surface free of shoulders, notches, grooves and the like. The tool comprises an elongated handle having thereon a surface capable of administering blows to the cutting end of the tool for installation purposes. One end of the tool has a pivoting assembly affixed thereto which is capable of being placed about the bit body and engaging the bit body in a wedging action when a pulling force is applied to the assembly by the tool handle. The tool handle may be provided with cam surfaces adapted to engage the exterior surface of the bit mounting means and to aid in the application of the pulling force on the pivoted assembly.

**MEANS FOR REMOVAL AND INSTALLATION OF
BITS IN MINING AND DIGGING MACHINERY**

**CROSS REFERENCE TO RELATED
APPLICATIONS**

This is a continuation-in-part of the copending application of the same inventor, Ser. No. 842,791, filed June 30, 1969 and entitled CUTTER BITS AND MEANS FOR MOUNTING THEM (now U.S. Pat. No. 3,622,206), which, in turn, is a continuation-in-part of the copending application in the name of the same inventor, Ser. No. 753,398, filed Aug. 19, 1968 and entitled CUTTER BITS AND MEANS FOR MOUNTING THEM, now abandoned.

BACKGROUND OF THE INVENTION

1. Field of the Invention

The invention relates to tools for the removal and installation of bits in mining and digging machinery, and more particularly to tools for the removal and installation of bits of the type wherein that portion of the bit body which extends outwardly of the bit mounting means and is engageable by a tool has a smooth, uninterrupted exterior surface free of shoulders, notches, grooves and the like.

2. Description of the Prior Art

In this specification the tools of the present invention will be described primarily as applied to the removal and installation of bits of mining machines. It will be understood, however, that the tools of the present invention are equally applicable to similar bits or digger teeth of excavating and earth working machinery. Hence, the term "bit" is intended to encompass digger teeth and the like.

Prior art workers have devised many forms of bits, digger teeth and the like. The bits have been of two basic varieties. First, there are those which have elongated body portions adapted to be received in a shank receiving perforation in a mounting means and are captively and non-rotatively held therein. A second variety is similarly provided with an elongated body portion adapted to be received and captively held in the shank receiving perforation of a mounting means. In this instance, however, the elongated body portion is of circular cross section, as is the shank receiving perforation in the mounting means. The diameter of the elongated bit body portion is so dimensioned as to render the bit freely rotatable within the shank receiving perforation of the mounting means. With both varieties of bits, it is necessary to provide a retaining means to assure that the bit will not be removed from the shank receiving perforation of its mounting means during the cutting operation. Some retaining means are of the type which must be physically disengaged from the bit, the bit then being free to be removed from the shank receiving perforation of its mounting means by hand or through the use of a tool. Sometimes, although the retaining means has been disengaged from the bit, it is necessary to use a tool to dislodge the bit from its shank receiving perforation. This is true because the bit has become jammed in its shank receiving perforation through the action of corrosive mine waters, accumulated fines and foreign material, or the like.

Prior art workers have also devised resilient retaining means, for both rotatable and non-rotatable bits, which provide a "knock-in, pry-out" relationship between the bit and its mounting means. Under such circumstances,

a bit may be inserted in the shank receiving perforation of its mounting means simply by the application of blows to its cutting end. The bit may be removed by simply pulling or prying it from its shank receiving perforation with a suitable tool.

Heretofore, bits of both varieties have been characterized by the fact that that portion of the bit body which extends outside the mounting means has had thereon a shoulder, notch, groove, or the like, which could be engaged by an appropriate prying or pulling tool. More recently, however, bits of both varieties have been developed in which that portion of the bit body which extends outside the mounting means is free of shoulders, notches, grooves or the like. Such bits have a number of advantages. First of all, they can be manufactured more simply and less expensively. Generally, they are formed from bar stock of any suitable cross sectional configuration. As a consequence, the amount of machining required to produce such bits is minimized. In addition, such bits are stronger and have a greater service life since they have fewer stress raising changes in diameter and in many instances none at all.

Exemplary forms of rotatable bits of the type just described are taught in United States Letters Patent Nos. 3,397,012 and 3,397,013. Exemplary types of such cutter bits, but of the non-rotatable type, are taught in the above mentioned U.S. Pat. No. 3,622,206 of which this application is a continuation-in-part.

Despite their many advantages, such bits have the disadvantage that there is no shoulder, notch, groove or the like on that part of their body which extends outside their mounting means. As a consequence, it is difficult (and sometimes impossible) to engage such bits with conventional tools to remove the bits from their mounting means. Thus, while such bits are frequently used with resilient retainers and have a "knock-in, pry-out" relationship with their mounting means, there has been no tool available to take full advantage of this relationship.

To this end, the present invention is directed to tools for inserting and removing such bits from their mounting means. The tools of the present invention are simple and inexpensive to manufacture; require little operating room; are easy to manipulate and are very effective to permit the insertion and removal of such tools with a minimum of effort.

SUMMARY OF THE INVENTION

The present invention relates to tools for the removal and insertion of bits in their mounting means. The bits may be of the rotatable or non-rotatable type. The tools of the present invention are particularly adapted for use with bits having a body portion extending from their respective mounting means, which body portion is free of shoulders, notches, grooves and the like.

The tools of the present invention comprise an elongated handle which may have a portion thereon adapted to administer blows to the cutting end of a bit during insertion of a bit in the shank receiving perforation of its mounting means. At one end of the elongated handle there is a pivoted assembly capable of being placed about that portion of a bit which extends outwardly of its mounting means. When a pulling or prying force is exerted on the pivoted assembly by the tool handle, the pivoted assembly will grasp the bit in a wedging action.

In one embodiment, the pivoted assembly of the tool comprises a simple loop-like structure. In another embodiment, that portion of the loop-like structure which is pivotally affixed to the tool handle is bifurcated with a toothed dog pivotally affixed therebetween. The tooth dog increases the grip exerted on the bit by the pivoted structure.

In other embodiments, the end of the tool, bearing the pivoted structure, is also provided with one or more cam surfaces extending rearwardly of the pivoted structure and increasing the pulling or prying force applied to the pivoted structure by the tool handle. In yet another embodiment, similar to the embodiments just described, the cam surfaces extend toward the pivoted structure so that the cam surfaces will lie adjacent the bit axis during the bit removal procedure.

In another embodiment of the tool of the present invention, that end of the tool handle bearing the pivoted structure is provided with a head portion having a depression therein adapted to receive the cutting end of the bit. The other end of the tool handle is provided with an enlarged nut. Between the head portion at one end of the handle and the enlarged nut at the other end of the handle there is captively affixed to the handle a sliding hammer capable of administering blows either to the head portion of the handle or the enlarged nut at the other end of the handle. Spring means may be provided to bias the pivoted structure to a position wherein it is out of the way of the depression in the head portion of the tool. During the insertion process, the bit is inserted in the shank receiving perforation of its mounting means and the tool is located with the cutting end of the bit in the depression in the head portion of the tool. The sliding hammer is then used to administer blows to the head portion of the tool, driving the bit home in its shank receiving perforation.

During the extraction process, the pivoted assembly is moved to its working position against the force of the above mentioned spring and is placed about the bit body, the cutting end of the bit extending into the depression in the head portion of the tool. The spring will tend to hold the pivoted structure in place on the bit body, freeing one of the operator's hands to manipulate the sliding hammer. The sliding hammer is used to apply blows to the enlarged nut at the opposite end of the tool handle, thus applying a pulling force of the pivoted structure, causing the bit to be extracted from the shank receiving perforation of its mounting means.

BRIEF DESCRIPTION OF THE DRAWINGS

FIG. 1 is a side elevational view of an exemplary form of a non-rotatable bit and the mounting means therefor.

FIG. 2 is a side elevational view, partly in cross section, illustrating an exemplary form of rotatable bit and the mounting means therefor.

FIG. 3 is a perspective view of a tool of the present invention for installing and removing bits of the type shown in FIGS. 1 and 2 into and from their respective mounting means.

FIG. 4 is a fragmentary side elevational view of the bit mounting means assembly of FIG. 1, illustrating (partly in cross section) the tool of FIG. 3 and its use.

FIG. 5 is a side elevational view and illustrates a modified form of the tool of FIG. 3.

FIG. 6 is a fragmentary perspective view of another embodiment of the tool of the present invention.

FIG. 7 is a fragmentary view of a bit-mounting means assembly of FIG. 1 illustrating the use of the tool of FIG. 6.

FIG. 8 is a fragmentary perspective view of another embodiment of the tool of the present invention.

FIG. 9 is a fragmentary plan view illustrating yet another embodiment of the tool of the present invention.

FIG. 10 is a fragmentary side elevational view (partly in cross section) illustrating a bit-mounting means of the type shown in FIG. 2 and the tool of FIG. 9, as applied thereto.

FIG. 11 is a fragmentary side elevational view of the bit-mounting means of FIG. 1 and the tool of FIG. 9 as applied thereto.

FIG. 12 is a fragmentary side-elevational view of yet another embodiment of the tool of the present invention.

FIG. 13 is a fragmentary side elevational view of the head portion of the tool of FIG. 12, with the pivoted assembly removed.

FIG. 14 is a fragmentary plan view of the head portion of the tool of FIG. 12.

FIG. 15 is an end elevational view of the tool of FIG. 12, illustrating the head portion and pivoted assembly thereof.

FIG. 16 is a fragmentary side elevational view illustrating the use of the tool of FIG. 12 to insert a bit of the type shown in FIG. 2.

FIG. 17 is a fragmentary side elevational view similar to FIG. 16, and illustrating the use of the tool of FIG. 12 to extract a bit of the type shown in FIG. 2.

FIG. 18 is a fragmentary side elevational view illustrating the use of the tool of FIG. 12 to extract a bit of the type shown in FIG. 1.

DESCRIPTION OF THE PREFERRED EMBODIMENTS

FIG. 1 illustrates an exemplary form of bit-mounting means assembly wherein the bit is of the non-rotatable type, as taught in the above mentioned U.S. Pat. No. 3,622,206 of which the present application is a continuation-in-part application. The bit is generally indicated at 1 and the lug is generally indicated at 2. The lug comprises a body 3.

The body 3 has a shank receiving perforation 4. The axis of the shank receiving perforation 4 is inclined toward the cutting direction (indicated by arrow A). The angle between the shank receiving perforation axis and the cutting direction may be 90° or less. An angularity of less than 90° (as shown) is generally preferred so that the component of force tending to shove the bit into the shank receiving perforation is greater and so that the resultant cutting stresses on the bit may be more nearly in line with the bit axis.

The bit comprises an elongated shank 5 of any suitable cross section. The upper end of the shank terminates in a clearance surface 6 lying at an angle to the shank axis and is relieved on opposite sides (one such relief being shown at 7) so as to form a cutting tip 8 having a cutting surface 9 substantially parallel to the axis of the shank 5. The bit may be provided with a hard cutting tip, as shown at 8a in FIGS. 11 and 18. The lower end of the shank 5 terminates in an abutment surface 10 lying at an angle to the shank axis.

The lug body 3 has a transverse hole 11 extending through the body and intersecting the shank receiving perforation 4. A pin 12 is located in the hole 11 and

may be replaceably held or permanently affixed therein as by welding or the like. The pin 12 may have a length equal to or less than the length of the hole 11. The pin 12 is relieved to form an abutment surface 13 adapted to cooperate with the abutment surface 10 on the cutter bit. The abutment of surfaces 10 and 13 serve not only to determine the gauge or depth to which the bit extends into the shank receiving perforation 4, but also to render the bit non-rotatable by virtue of the angularity of these abutting surfaces.

FIG. 1 also illustrates an exemplary form of resilient retaining means for maintaining the shank 5 in the shank receiving perforation 4. In this instance, the inside surface of the perforation 4 has an annular notch or groove 14 formed therein. The notch 14 is adapted to receive one or more resilient C-shaped elements of metal or the like. For purposes of an exemplary showing, two C-shaped metal elements 15 and 16 are illustrated. The elements 15 and 16 are substantially identical. They have an outside diameter greater than the shank receiving perforation but slightly less than the diameter of the annular notch 14. The rings 15 and 16 have an inside diameter slightly less than the diameter of the bit shank 5. In use, the C-shaped elements are contracted (which can be accomplished by virtue of the fact that the ends of each element are spaced from each other) and are shoved into the shank receiving perforation 4 until they reach the annular notch or groove 14. When the notch 14 is reached, the C-shaped elements are captively held in the notch or groove 14.

The bit 1 may be mounted in the mounting means 2 by inserting it into the shank receiving perforation. Since the diameter of the bit 5 is greater than the inside diameter of the elements 15 and 16, the bit must be forced therethrough. A blow by a tool will be sufficient to cause the bit 1 to assume its proper seated position against the abutment surface 13 as shown in FIG. 1. The elements 15 and 16 frictionally engage the shank 5 and prevent removal thereof by centrifugal force or other forces operating to remove the bit. During normal cutting conditions, there will be a large component of force tending to urge the bit toward its seated position.

Removal of the cutter bit 1 may be accomplished by engaging the exposed portion of the bit by a tool of the present invention and pulling upwardly thereon. Thus, the bit 1 has a "knock-in, pry-out" relationship with its mounting means 2.

FIG. 2 illustrates an exemplary form of rotatable bit and mounting means therefor, of the type taught in the above mentioned United States Letters Patent Nos. 3,397,012 and 3,397,013. The bit, generally indicated at 17 and the mounting means, generally indicated at 18, are typical of the rotatable bitmounting means structure to which the tools of the present invention are directed.

The bit 17 comprises an elongated body or shank 19 having a circular cross section. At one end, the shank 19 terminates in an abutment surface 20. At the other end, the shank 19 terminates in a nose portion 21 which may be provided with a hard cutting tip 22. The mounting means 18 has a body portion 23 having a forward surface 24 and a rearward surface 25. A shank receiving perforation 26 extends between the surfaces 24 and 25. The mounting means has a rearward extension 27 terminating in an upwardly extending anvil portion 28, having thereon an abutment surface 29 adapted to

cooperate with the bit abutment surface 20. Abutment surfaces 20 and 29 serve to determine the gauge or depth to which the shank 19 extends into the shank receiving perforation 26.

5 The diameter of the shank 19 and the diameter of the shank receiving perforation 26 are so sized that the bit 17 is freely rotatable with respect to its mounting means.

A number of resilient retaining means may be used 10 in such an assembly to provide a "knock-in, pry-out" relationship between the bit 17 and its mounting means 18. Since the nature of the resilient retaining means does not constitute a limitation on the present invention, for purposes of explanation, a retaining means of 15 the type taught in United States Letters Patent No. 2,965,365 has been illustrated.

The mounting means is provided with a transverse hole 30 intersecting the shank receiving perforation 26. The transverse hole contains a resilient holding device 20 comprising a metallic rod 31 encased in a body of resilient substance 32, excepting upon one side at the portion where the rod traverses the shank receiving perforation 26. The shank 19 of the bit is provided with an annular notch 33. When the bit 17 is inserted in the shank receiving perforation 24 and driven home by 25 blows administered to the cutting end of the bit, the tapered portion 19a of the bit shank 19 will cause the metallic rod 31 to be depressed into surrounding body of 30 resilient substance 32 to provide clearance in the shank receiving perforation 26 for the bit shank 19. When the bit has been driven to its seated position, the notch 33 35 therein will lie adjacent the rod 31 and the rod will be free to snap into the notch 33 and thus retain the bit in its shank receiving perforation. When a pulling force is applied to bit 17 to remove it from the shank receiving perforation 26, the notch is configured to deflect the rod 31 out of the shank receiving perforation 26, freeing the bit for removal.

40 In both of the bit-mounting means assemblies of FIGS. 1 and 2, it will be apparent that that portion 1a of bit 1 which extends beyond mounting means 2 and that portion 17a of bit 17 which extends beyond mounting means 18 are free of shoulders, notches,

45 grooves or the like by which the bits 1 or 17 could be engaged by conventional tools. FIG. 3 illustrates one embodiment of the tools of the present invention applicable to the insertion and removal of bits of the type shown in FIGS. 1 and 2. The tool, generally indicated

50 at 34, comprises a shank or handle 35. One end of the shank has a head 36 suitably configured to serve as a hammering device for knocking a bit into seated position within its shank receiving perforation. Preferably, the head 36 will comprise a socket element which contains a material 37 which is relatively soft when compared with the metal of the bit. In this way, the bit will not be damaged when blows are administered to it by the tool. The material 37 may be of any suitable nature. For example, it can comprise a body of rolled and compressed leather or rawhide, a body of soft metal, a body 55 of resilient rubbery substance, a body of wood or the like.

The other end of the shank 35 has a ring-like member 38 pivotally affixed thereto by means of a pin or the like 39. FIG. 4 more clearly illustrates the ring 38 and its use. For purposes of an exemplary showing, a bitmounting means assembly of the type shown in FIG. 1

is illustrated, and like parts have been given like index numerals.

The ring 38 has an internal diameter slightly larger than the diameter of the bit 1, so that the ring may be readily placed about the bit as illustrated. The ring has a rearwardly extending shank 40 which lies between bifurcations 41 and 42 at the end of the tool shank. The pivot pin 39 extends through coaxial perforations in the bifurcations 41 and 42 and the ring shank 40. It will be understood by one skilled in the art that it would not constitute a departure from the present invention to provide the ring 38 with a pair of spaced shanks, adapted to lie on either side of the end of the tool shank 35 and to be pivotally affixed thereto.

As will be evident from FIG. 4, when an upward pulling force is applied to the tool shank 35, the pivoted ring 38 will engage the bit portion 1a as at 43 and 44 with a sort of wedging action. Having thus been engaged, the bit 1 can be pulled from the shank receiving perforation of the mounting means 2. Since the ring 38 frictionally engages the bit as at 43 and 44, the inside edges of the ring should be relatively sharp to ensure a better engagement.

In FIG. 5, the tool shank, the ring, the bit and the mounting means are substantially identical to that shown in FIG. 4 and like parts have been given like index numerals. In this instance however, the bifurcations of the tool shank are enlarged (one of which is shown at 42a) so as to provide a cam surface 45 adapted to cooperate with the top surface 46 of the mounting means 2. Removal of the bit 1 is accomplished in the same manner described with respect to FIG. 4, except that the pulling force is accomplished by rocking the tool handle on the cam surface 45, the cam surface 45, in turn, rocking on the mounting means surface 46. It will be understood by one skilled in the art that the embodiment of FIGS. 3 and 4 can be used with the bit-mounting means assembly of FIG. 2 in the same manner as described. Similarly, the embodiment of FIG. 5 can be used, the cam surface 45 operating on the front surface 24 of the mounting means 18 of FIG. 2.

In FIG. 4 the handle 35 of the tool is shown to the rear of the bit. In FIG. 5 the handle 35 is shown in front of the bit. It will be understood by one skilled in the art that the tool may be oriented anywhere about the bit where the ring 38 can adequately engage the bit. The embodiment of FIG. 5 is shown in its preferred position because the slope of the bit axis will cooperate with the prying action of the tool.

FIGS. 6 and 7 illustrate another embodiment of the present invention. FIG. 7 shows this embodiment as applied to a bit-mounting means assembly of the type shown in FIG. 1 (again, like parts have been given like index numerals).

In this instance, a tool shank 47 is shown, equivalent to the tool shank 35 in FIG. 3. The bottom end of the shank 47 is reduced in width as indicated at 48. A circular ring 49 is shown, having a pair of spaced rearwardly extending shanks 50 and 51, adapted to be pivotally affixed to the portion 48 of tool shank 47 by a pivot pin or the like 52.

Between the spaced rearwardly extending ring shanks 50 and 51 there is pivotally mounted a dog 53 by means of a pivot pin 54, the ends of which extend into perforations in the ring shanks 50 and 51. The dog has a series of teeth 55. When the dog is in the position

shown in FIGS. 6 and 7, the distance between the dog teeth 55 and the diametrically opposed inside surface of the ring 49 is slightly less than the diameter of the bit 1. Spring means 56 may be engaged on the pivot pin 54 with one end 58 engaging the bottom surface of the dog, and the other end 58 engaging the top surface of the ring shank 50. The spring means 56 will tend to pivot the dog upwardly toward a position where the teeth 55 do not extend into the inside opening of the ring 49.

The use of the embodiment of FIGS. 6 and 7 is substantially the same as that described with respect to FIG. 4. The difference lies in the fact that the bit 1 will be engaged by the ring as at 59 and by the dog teeth 55, as illustrated. Such an arrangement is particularly desirable when the bit 1 is made of very hard and durable material. Again, the tool may be oriented anywhere about the bit where the ring 49 and dog teeth 55 can adequately engage the bit.

It will be understood by one skilled in the art that the reduced portion 48 of the tool shank 47 may be provided with configuration similar to the configuration of the bifurcations in FIG. 5. Thus, a cam surface would be presented (as shown in dotted lines at 48a) adapted to cooperate with the upper surface 46 of the mounting means 2.

The embodiment of FIGS. 6 and 7 may be used with a bit-mounting means assembly of the type shown in FIG. 2. When it is so used, its use will be identical to that described with respect to FIG. 7.

FIG. 8 illustrates in perspective another type of tool for use with "knock-in, pry-out" bits or digger teeth. The tool of FIG. 8, generally indicated at 60, comprises a handle 61 which may have any desired configuration and a bifurcated head portion generally indicated at 62. The bifurcations 63 and 64 are spaced from each other by a distance substantially equal to or greater than the width of the bit to be removed. The bifurcations 63 and 64 are provided with extensions (one of which is shown at 65) which are adapted to engage a surface on the mounting means and act as cams during the pry-out operation.

A generally U-shaped member 66 is pivotally affixed to the tool head 62 by pivot pin 67. The pivot pin extends through coaxial perforations at the ends of the legs of the U-shaped member 66 and in the bifurcations 63 and 64. A central portion 68 of the pin 67 extends between the bifurcations 63 and 64.

The inside surface of the U-shaped member 66 may be provided with two or more pointed extensions. Two such pointed extensions are shown at 69 and 70. The pointed extensions may be made of hardened metal and the like and appropriately affixed to the U-shaped member 66. Alternatively, the pointed extensions 69 and 70 may be integral with the member 66 and the entire member may be made of hardened material. It will be understood that the pointed extensions 69 and 70 generally are directed toward the central portion 68 of the pivot pin 67.

The operation of the tool of FIG. 8 may be described as follows. When a bit or digger tooth is to be removed from its mounting means, the U-shaped member 66 is placed over the bit and the bit is engaged between the pointed extensions 69 and 70 and the central portion 68 of the pivot pin 67. The tool is so configured as to cause the bit to be engaged relatively near the forward end of the shank receiving perforation in the bit mount-

ing means. As the tool handle 61 is moved in the direction of arrow B, the pointed extensions 69 and 70 are caused to dig into the bit body because of the resultant diminishing horizontal distance between the pointed extension 69 and 70 and the central portion 68 of pivot pin 67.

After the pointed extensions 69 and 70 have penetrated the bit shank, continued movement of the tool handle 61 in the direction of arrow B will cause the bit body to be lifted from the shank receiving perforation of the mounting means. The bit body may be removed in increments, if desired, by performing the above described operations a number of times. Again, the tool may be oriented about the bit in any position where it can get an adequate purchase on the bit and where the extensions 65 on bifurcations 63 and 64 can properly contact the mounting means. An approach from the front of the bit (as in FIG. 5), where possible, will again put the prying forces more nearly in line with the bit shank axis.

In all of the embodiments shown in FIGS. 5 through 8, the tool shanks or handles may or may not be provided with one or more surfaces capable of administering blows to the cutting end of a bit during the bit insertion process. The provision of such a pounding surface (as for example, head means 36 in the embodiment of FIG. 3) is desirable primarily as a matter of convenience, so that one tool may be used for both the insertion and removal of the bits. It will further be understood by one skilled in the art that the pivoted assemblies on those tools may have any appropriate configuration and may have a central opening which again may be of any configuration. Such configuration is based largely on the cross sectional configuration of the bit to be extracted.

FIGS. 9 through 11 illustrate yet another embodiment of the tool of the present invention. In this instance, the tool comprises an elongated handle 71. A pair of spaced extensions are affixed to one end of the handle as by welding or the like. Such extensions are shown at 72 and 73. In addition, a socket 74 may be provided for material presenting a pounding surface 75. It will be understood that the pounding surface 75 may be made up of any of the materials described with respect to pounding surfaces 37 in FIG. 3.

The extensions 72 and 73 are spaced by a distance slightly greater than the diameter of the bit with which the tool is to be used. In addition, the extensions 72 and 73 are of such length that that portion of the bit extending outside the shank receiving perforation of its mounting means can be accommodated therebetween. The free ends of extensions 72 and 73 are provided with perforations 76 and 77, respectively, through which a pivot pin 78 extends. Those ends of pivot pin 78 which extend beyond extensions 72 and 73 pass through perforations 79 and 80 in the ends of a U-shaped member 81. Thus, the U-shaped member 81 is pivotally affixed to the free end of extensions 72 and 73. The pivot pin 78 may be held in place by C-shaped retaining means 82 and 83, of well known type, or by any other suitable means.

The U-shaped element 81 may be provided with a pointed extension 84 opposite the central portion of pivot pin 78. While again, the pointed extension 84 may be an integral part of the U-shaped element 81, it is shown as being an insert of carbide or hard metal, let into a perforation 85 in the U-shaped member. It will

be understood that the distance between the central portion of pivot pin 78 and the pointed extension 84 will be slightly greater than the diameter of the bit to be removed.

As is most clearly seen in FIGS. 10 and 11, the free ends of extensions 72 and 73 are provided with laterally extending cam elements 86 and 87, respectively, having cam surfaces 86a and 87a, respectively.

FIG. 10 illustrates a bit and mounting means of the type shown in FIG. 2, and like parts have been given like index numerals. The Figure illustrates the manner in which the tool of FIG. 9 is used to extract bit 17. The U-shaped member 81 is located about the bit 17 with the lower surface of the U-shaped member lying against the forward surface 24 of the mounting means 18. The bit 17 is therefore located between the pointed extension 84 and the central portion of pivot pin 78.

As the tool is moved in the direction of arrow C, the cam surface 86a and cam surface 87a (not shown in FIG. 10) will operate on the forward surface 24 of the mounting means 18 to apply a pulling force on the U-shaped member 81. At first, the forward portion 17a of the bit shank 19 will be gripped in a wedging action between pivot pin 78 and the pointed extension 84, the pointed extension biting into the surface of the bit shank. Thereafter, further movement of the tool in the direction of arrow C will, through the action of the cam surfaces on the tool and the forward surface 24 of the mounting means, lift or pry the bit 17 from the shank receiving perforation 26.

FIG. 11 illustrates the tool of FIG. 9 as applied to the bit-mounting means assembly of FIG. 1, again like parts having been given like index numerals. In this instance, the U-shaped member 81 is placed about the bit 11 so that the bit is located between the pointed extension 84 and the pivot pin 78. The U-shaped member 81 rests on the upper surface 46 of the mounting means 2. When the tool is pivoted in the direction of arrow D, the bit 1 will be extracted from the mounting means 2 in the same manner described with respect to FIG. 10, through the interaction of the tool cam surfaces 86a (not shown) and 87a and the top surface 46 of the mounting means 2. While for purposes of an exemplary showing the handle 73 is illustrated as being to the rear of the bit 1 in FIG. 11, and while the tool will function well in this position, where possible it may be preferred to locate the handle of the bit at the front of the bit (as in FIG. 5) so that the prying forces will be more nearly in line with the bit shank axis.

It will be understood by one skilled in the art that the tool of FIGS. 9 through 11 has several advantages. First of all, it will be noted that the tool cam surfaces 86a and 87a lie adjacent the axis of the bit to be removed. By virtue of this and the shape of the cam surfaces, a greater throw is achieved so that the bit may normally be removed by a single operation of the tool. In addition, the tool of FIGS. 9 through 11 requires less surface on the mounting means with which the tool camming surfaces interact. Therefore, if the forward surface 24 of the mounting means of FIG. 10 or if the top surface 46 of the mounting means of FIG. 11 is relatively small, the tool of FIGS. 9 through 11 can be used to greater advantage than can the embodiments of FIGS. 5 and 8, for example.

Where the bit axis lies at 90° to the adjacent surface of the mounting means (as for example in the bit-mounting means assembly of FIG. 10), it will be under-

stood that the tool may be placed at any orientation about the bit.

FIGS. 12 through 18 illustrate yet another embodiment of the tool of the present invention.

The tool comprises an elongated handle or shank 88 having a head member 89 affixed to one end thereof and an enlarged nut 90 affixed to the other end thereof. The handle 88 has, captively mounted thereon, a sliding hammer 91. The hammer 91 is adapted to apply blows either to the surface 92 of the head member 89 or to the surface 93 of the nut 90, as will be explained hereinafter.

As is most clearly shown in FIG. 13, the head member 89 has a forward surface 94 having a depression 95 therein, adapted to receive the cutting end of the bit. The head member 89 also has a longitudinal flat or relief 96 with a forwardly extending lug 97 permanently affixed thereto. The lug 97 has a perforation 98 extending therethrough.

The perforation 98 is adapted to receive a pivot pin 99. The ends of the pivot pin 99 pass through perforations 100 and 101 in the arms of a U-shaped member 102. Thus, the U-shaped member 102 is pivotally affixed to the forwardly extending lug 97. Again, the pivot pin 99 may be held in place by C-shaped retaining rings 103 and 104 at its ends, or by any other suitable means.

The U-shaped member 102 is substantially similar to the member 91 of FIG. 9. Again, a pointed extension 105 may be provided. The extension 105 may be an integral part of the U-shaped member 102 or it may be a hard metal or carbide insert let into a perforation 106 in the U-shaped member.

A spring 107 may be mounted on pivot pin 99. The spring has one arm 108, the end of which extends into a perforation 109 in the forward face 94 of the head member 89. The spring 106 has a second arm 110 which engages the top surface of U-shaped member 102, as shown. The spring 108 serves to bias the U-shaped member to a position where it lies in abutting relationship with the flat 96 on the head member 89. Thus, the U-shaped member 102 is normally out of the way of the forward surface 94 of the head member 89 and the depression 95 therein.

FIG. 16 illustrates the use of this tool with the bit-mounting means assembly of FIG. 2 (like parts having been given like index numerals). The tool is shown in the position it will assume during the bit insertion procedure. The bit 17 is placed in the shank receiving perforation of the mounting means 18 and the tool is placed on the bit, with the bit nose 21 in the depression 95 of the tool head member 89. The operator grasps the tool with one hand and grasps the sliding hammer 91 (FIG. 12) on the tool with the other. The operator then causes blows to be administered by the sliding hammer 91 to the surface 92 of the head member 89 of the tool. The interaction of the depression 95 in the tool head member and the nose 21 of the bit will cause the bit to be seated in its shank receiving perforation.

FIG. 17 is similar to FIG. 16 and like parts have been given like index numerals. FIG. 17 differs from FIG. 16 in that it shows the position of the tool during the bit extraction process. In this instance, the tool operator pivots the U-shaped member 102 in the direction of arrow E and against the action of spring 107 (not shown). The U-shaped member 102 is then placed about the body portion 16a of the bit 17 as shown. This

is made possible by the fact that the nose 21 of the bit is received, in part at least, in the depression 95 in the head member 89 of the tool.

Since the portion 102 is pivoted in the direction of arrow E against the action of spring 107, it will tend to maintain the position shown in FIG. 17. Therefore, again the operator is free to grasp the tool with one hand and the sliding hammer thereof with the other. In this instance, the operator will use the hammer to administer blows to the surface 93 of the nut 90 (FIG. 12).

Bit body portion 17a is engaged between forwardly extending lug 97 and the pointed extension 105. Blows, administered to the surface 93 of the nut 90 will first cause the pointed extension 105 to bite into the bit surface and then will cause the bit 17 to be removed from the shank receiving perforation.

FIG. 18 illustrates the use of this tool with the cutter bit-mounting means assembly of FIG. 1 (like parts having been given like index numerals). In this instance, the head member 89 of the tool is provided with a depression 95a in its forward face 94 suitably configured to cooperate with the cutting end of bit 1. Thus, the tool may be used to insert the bit 1 in the shank receiving perforation of its mounting means 2 in a manner identical to that described with respect to FIG. 16.

FIG. 18 illustrates the tool in its position when used to extract bit 1 from the shank receiving perforation of mounting means 2. The use of the tool and its operation is identical to that described with respect to FIG. 17.

It will be understood by one skilled in the art that the tool of FIGS. 12 through 18 has a number of advantages. First of all, it is compact, easy to use and inexpensive to manufacture. In addition, it does not depend upon an interaction with any surface on the bit mounting means. The sliding hammer makes the tool positive in its action and enables the tool to insert or extract a bit very rapidly.

Finally, it will be understood by one skilled in the art that the forward surface 94 of the head member 89 of the tool may be provided with a simple, depression of any shape. For example, the depression could be cylindrical or rectangular and have the innermost portion thereof filled with material of the type described with respect to elements 37 in FIG. 3. Under these circumstances, the tool could be used with a number of different types of bits having differently configured cutting ends.

Modifications may be made in the invention without departing from the spirit of it. As indicated above, for example, all embodiments may be provided with a surface or means suitable to administer blows to the bit during the bit installation process. Similarly, the various embodiments of the present invention may have a spring means similar to the spring 107 on the embodiment of FIGS. 12 through 18. For example, such a spring is shown at 111 in the embodiment of FIG. 8. The spring 111 may be mounted on the pivot pin 67 between the bifurcation 74 and the adjacent leg of the U-shaped member 66. One end 111a of the spring is hooked over the last mentioned leg. The other end of the spring 111b is anchored in a perforation in the extension 65. The spring will normally retain the U-shaped member against the bifurcated head portion 62 in a position generally indicated at 112. Thus the U-shaped element 66 will be kept out of the way until needed. The spring 111 will also assist in properly posi-

tioning the U-shaped member 66 and pointed extensions 69 and 70 to maintain a grip on the bit, particularly where the bit is removed in increments.

The embodiments of the invention in which an exclusive property or privilege is claimed are defined as follows:

1. A tool for the removal of a bit from the shank receiving perforation of its mounting means wherein the bit is of the type having a body portion extending beyond that surface of the mounting means surrounding said shank receiving perforation, said bit body portion having a smooth peripheral surface free of shoulders, notches, grooves and the like, said tool comprising an elongated handle with first and second ends, means configured to extend about said body portion of said bit, said means having spaced ends pivotally affixed to said first handle end, additional means at said first handle end between said ends of said pivoted means, said pivoted means and said additional means being so related as to engage said bit body portion at at least two places with a wedging action when a pulling force is applied to said pivoted means by said handle, whereby said bit may be engaged and pulled from said shank receiving perforation by said tool.

2. The structure claimed in claim 1 including a surface on said handle by which blows may be administered to said bit for installation of said bit in said shank receiving perforation of said mounting means.

3. The structure claimed in claim 1 wherein said pivoted means comprises a split ring-like structure, the end of said split ring terminating in spaced rearwardly extending shanks, said shanks being located on either side of said first end of said tool handle and being pivotally affixed thereto, a dog comprising said additional means and being pivotally affixed at one end between said shanks, the other end of said dog being toothed, said split ring having an internal diameter such that said body portion of said bit may be received therein, said dog being pivotable to a position wherein said bit body portion when located within said split ring is engaged in a wedging action by said toothed end of said dog and the diametrically opposed portion of said split ring when a pulling force is applied to said split ring by said tool handle.

4. The structure claimed in claim 1 wherein said first end of said tool handle is bifurcated, said pivoted means comprising a U-shaped member, each end of said U-shaped member being pivotally affixed to an adjacent one of said bifurcations by a pivot pin having a central portion extending between said bifurcations and end portions extending through coaxial perforations in said bifurcations and the adjacent ends of said U-shaped member, means to prevent axial movement of said pin, said central portion of said pin comprising said additional means, said bit body portion being engaged in a wedging action by said central portion of said pin and the diametrically opposed portion of said U-shaped member when a pulling force is applied to said pin and said U-shaped member by said handle means, whereby said bit may be extracted from said shank receiving perforation.

5. The structure claimed in claim 1 wherein said first and second ends of said tool handle are enlarged, the remainder of said handle therebetween being of uniform cross sectional dimension, said first end having a front surface with a recess therein adapted to receive the forward end of said bit, said first end having a lug

thereon comprising said additional means, the front end of said lug extending forwardly of said front surface, said pivoted means comprising a U-shaped member, the ends of said U-shaped member lying on either side of said front end of said lug and being pivotally affixed thereto, said U-shaped member being swingable between a first position in front of and in a plane substantially parallel to said front surface of said first end of said tool handle and a second position along the side of said first end and in a plane substantially parallel to the axis of said tool handle, a hammer means being captively mounted on said portion of said tool handle of uniform cross sectional dimension and being slidable therealong between said first and second enlarged ends, whereby said bit may be partially inserted in said shank receiving perforation and said first end or said tool may be placed on said bit with said front end of said bit in said recess and said U-shaped member in said second position, said bit being driven to its seated position in said shank receiving perforation by blows administered to said first tool end by said hammer means, and whereby said tool may be placed on said bit when said bit is seated in said shank receiving perforation with said U-shaped member in said first position and said bit forward end in said recess, said bit being engaged in a wedging action by said front end of said lug and a diametrically opposed portion of said U-shaped member and removed from said shank receiving perforation by a pulling force exerted on said U-shaped member by blows administered to said second tool handle end by said hammer means.

6. A tool for the removal of a bit from the shank receiving perforation of its mounting means wherein the bit is of the type having a body portion extending beyond that surface of the mounting means surrounding said shank receiving perforation, said bit body portion having a smooth peripheral surface free of shoulders, notches, grooves and the like, said tool comprising an elongated handle with first and second ends, a ring-like structure pivotally affixed to said first end of said tool handle, said ring-like structure having an internal diameter such that said body portion of said bit may be received therein when said ring-like structure lies in a plane normal to the axis of said bit, said ring-like structure lying in a plane other than normal to said bit axis and engaging said body portion of said bit at diametrically opposite positions when a pulling force is applied to said ring-like structure by said tool handle, a cam surface on said first tool end adapted to cooperate with said mounting means surface whereby rocking of said handle about said cam surface on said mounting means surface will cause said tool handle to exert said pulling force.

7. The structure claimed in claim 3 including a cam surface on said first tool end adapted to cooperate with said mounting means surface whereby rocking of said handle about said cam surface on said mounting means surface will cause said tool handle to exert said pulling force.

8. The structure claimed in claim 4 including means on said diametrically opposed portion of said U-shaped member to bite into said bit body portion during said wedging action.

9. The structure claimed in claim 4 wherein each of said bifurcations has an extension thereon, a cam surface on each extension, said cam surfaces being configured to engage said mounting means surface to one side

of said shank receiving perforation therein when said U-shaped member is located about said bit body portion, whereby rocking of said tool handle about said cam surfaces on said mounting means surface will cause said tool to exert said pulling force.

10. The structure claimed in claim 4 wherein each of said bifurcations has an extension thereon, a cam surface on each extension, said cam surfaces being configured to engage said mounting means surface on opposite sides of said shank receiving perforation therein when said U-shaped member is located about said bit body portion, whereby rocking of said tool handle about said cam surfaces on said mounting means surface will cause said tool handle to exert said pulling force.

11. The structure claimed in claim 4 including a surface on said handle by which blows may be administered to said bit for installation of said bit in said shank receiving perforation of said mounting means.

12. The structure claimed in claim 4 including means to bias said pivoted U-shaped member to a position wherein said U-shaped member lies along said tool han-

dle and rearwardly of said first end whereby said biasing means prevents undesired movement of said U-shaped member when said member is not in use and augments said wedging action when said U-shaped member is in use.

13. The structure claimed in claim 5 including means on said diametrically opposed portion of said U-shaped member to bite into said bit body portion during said wedging action.

10 14. The structure claimed in claim 5 including means to bias said U-shaped member to said second position whereby said biasing means prevent undesired movement of said U-shaped member when said member is not in use and augments said wedging action when said

15 U-shaped member is in use.

16 15. The structure claimed in claim 5 wherein said portion of said handle between said first and second ends is of circular cross section, said hammer means comprising a cylindrical member having an axial hole through which said handle portion extends.
